UNITED STATES PATENT OFFICE.

THOMAS A. CONLON, OF SILVER SPRING, MARYLAND.

PEDESTAL MOUNT FOR GUNS.

Application filed January 30, 1924. Serial No. 689,469.

(FILED UNDER THE ACT OF MARCH 3, 1883, 22 STAT. L., 625.)

To all whom it may concern:

Be it known that I, THOMAS A. CONLON, a citizen of the United States, and a resident of Silver Spring, county of Montgomery, and State of Maryland, have invented an Improvement in Pedestal Mounts for Guns, of which the following is a specification.

The invention described herein may be used by the Government, or any of its officers or employees in prosecution of work for the Government, or by any other person in the United States, without payment to me of any royalty thereon, in accordance with the act of March 3, 1883.

The present invention relates to pedestal mounts for guns and particularly to that type of pedestal mount employed with anti-aircraft artillery.

20 In using large caliber guns and guns of the anti-aircraft type, it is absolutely essential for correct aiming that some means be provided in the gun mount for maintaining the cradle trunnions in a horizontal plane at all times when the gun is moving in azimuth. The structures employed, heretofore, for maintaining the true horizontal position of the cradle trunnions have been expensive to construct, difficult to operate and involve a multiplicity of complicated parts which readily get out of order.

The primary object of the present invention is to provide a leveling device for guns by means of which the gun cradle may be maintained at all times in a true horizontal position regardless of the configuration of the ground upon which the gun is mounted.

A further object of the invention is the provision of a gun mount in which ease of operation, simplicity and inexpensiveness of construction are distinguishing characteristics.

With the foregoing and other objects in view, my invention resides in the novel arrangement and combination of parts and in the details of construction hereinafter described and claimed, it being understood that changes in the precise embodiment of the invention herein disclosed may be made within the scope of what is claimed without departing from the spirit of the invention.

A preferred embodiment of my invention is illustrated in the accompanying drawing, in which,

Fig. 1 is a section on the line 1—1 of Fig. 55 2; and

Fig. 2 is a section on the line 2—2 of Fig. 1.

Referring to the drawing by numerals of reference;

I have shown a base 5 which may be positioned upon a permanent gun emplacement or upon a movable gun carriage. Mounted upon the base 5 and secured thereto as by means of bolts 6, is a pedestal 7. 60 A supporting member 8 mounted upon the pedestal 7 serves to carry the upper gun carriage with the cradle and gun attached thereto. This supporting member 8 is mounted on the pedestal 7 so as to have 70 universal movement with respect thereto, thus the pedestal 7 at its upper end may be formed with a socket 9 adapted to receive a ball-head 10, preferably, formed integral with the supporting member 8.

By moving the supporting member on the pedestal should the gun be found to be unevenly positioned, the cradle may be always maintained level. For moving the supporting member with respect to the pedestal, I 80 preferably employ a pair of movable members 11 and 12 mounted on the pedestal and reciprocable in paths at right angles to each other and connected to the supporting member 8 in such manner that the total movement of the reciprocating members is communicated to the supporting member so as to maintain the gun in its proper level position.

The movable member 11 in the preferred embodiment of my invention, is screw threaded so as to move upon an actuating bolt 13 mounted upon the pedestal as by means of brackets 14. For guiding the member 11 in its reciprocating movement, bars 15 may be provided, which are attached at either end to the brackets 14 and are mounted one on each side of the bolt 13. The movable member 12, in the preferred embodiment of my invention, reciprocates 90 in a groove 16 formed in the upper face of the member 11 and is guided in its reciprocable movement in the groove 16 between the walls 17 of the member 11 defining the groove. Any suitable means may be employed for actuating the member 12 in its reciprocating movement. As shown, the member 12 is formed with an internal 100

105

screw thread and is mounted upon a bolt 18 which is journaled at either end in the cross bars 19 of the member 11.

Any suitable means may be employed for connecting the movable members 11 and 12 to the supporting member 8 so that the movement of the members 11 and 12 may be communicated to the member 8 to maintain the gun in a true horizontal position.

10 As shown, the member 8 is formed at its lower end with a recess 20 adapted to receive a spheroidal connecting member 21 which is preferably formed integral with the movable member 12.

15 For actuating the members 11 and 12 rachets may be employed connected by collars 22 to the bolts 13 and 18, respectively. The rachets may be manipulated by levers 23 pivoted to the collars 22 and normally 20 held in inoperative position against the pedestal 7 by catches 24. Four rachets will be provided, preferably, one for either end of a bolt.

In operation, my device may be employed 25 as follows:

When the gun has been brought into position and it is found that the trunnions are not in a horizontal plane, the bolt 18 or the bolt 13 or both bolts will be actuated to 30 move the members 11 and 12 so as to correct the position of the cradle trunnions. In this way, the supporting member 8 will be moved and with the member 8 the cradle so that the gun at all times may be maintained 35 in a true horizontal position.

The pedestal forming the subject of this invention, is easy to construct, simple in operation and requires but a few easy working parts. It will not get out of order in 40 ordinary use and avoids the many difficulties met with in the leveling pedestals heretofore employed.

Having thus described my invention, what I claim is:

45 1. A leveling device for guns including a pedestal, a supporting member provided with a recess in its lower end mounted on the pedestal and adapted to have universal movement with respect thereto, a member 50 mounted on the pedestal and reciprocable in a rectilinear path in one plane, said member provided with a longitudinal groove transverse to its path of movement, a second member mounted on the first member 55 and adapted to move in rectilinear path in the groove of the first member and be guided thereby, means secured to the second member and adapted to seat in the recess of the supporting member to move the supporting 60 member on movement of the second member and means adapted to move each of the movable members.

65 2. A leveling device for guns including a pedestal, a supporting member provided with a recess in its lower end mounted on

the pedestal and adapted to have universal movement with respect thereto, a member mounted on the pedestal and reciprocable in one plane, said member provided with a longitudinal groove transverse to its path of movement, a second member mounted on the first member and adapted to move in the groove of the first member and be guided thereby, means secured to the second member and adapted to seat in the recess of the supporting member to move the supporting member on movement of the second member and means adapted to move each of the movable members.

3. A leveling device for guns including 80 a pedestal, a supporting member provided with a recess in its lower end mounted on the pedestal and adapted to have universal movement with respect thereto, a movable member on the pedestal and reciprocable 85 in a rectilinear path in one plane, means on the pedestal guiding this member in its reciprocable movement, a second movable member mounted on the first member and reciprocable in a rectilinear path in a plane 90 at right angles to the path of movement of the first member, means on the first member guiding the second member in its reciprocable movement, a spheroidal member secured to the second member and adapted to 95 seat in the recess of the supporting member and means adapted to move each of the movable members.

4. A leveling device for guns including 100 a pedestal, a supporting member provided with a recess in its lower end mounted on the pedestal and adapted to have universal movement with respect thereto, a movable member on the pedestal and reciprocable in one plane, means on the pedestal guiding 105 this member in its reciprocable movement, a second movable member mounted on the first member and reciprocable in a plane at right angles to the path of movement of the first member, means on the first member guiding the second member in its reciprocable movement, a spheroidal member secured to the second member and adapted to seat in the recess of the supporting member to move the supporting 110 member on movement of the second member and means adapted to move each of the movable members.

5. A leveling device including a pedestal, a supporting member provided with a recess 115 in its lower end mounted on the pedestal and adapted to have universal movement with respect thereto, a movable member mounted on the pedestal and reciprocable in a rectilinear path in one plane, a second 120 movable member mounted on the first member and reciprocable in a rectilinear path in a plane at right angles to the path of movement of the first member, means on the second member adapted to seat in the recess 125

of the supporting member, and means adapted to move each of the movable members.

6. A leveling device including a pedestal, 5 a supporting member provided with a recess in its lower end mounted on the pedestal and adapted to have universal movement with respect thereto, a movable member mounted on the pedestal and reciprocable in 10 one plane, a second movable member mounted on the first member and reciprocable in a plane at right angles to the path of movement of the first member, means on the second member adapted to seat in the recess of 15 the supporting member, and means adapted to move each of the movable members.

7. A leveling device including a pedestal, a supporting member mounted on the pedestal and adapted to have universal 20 movement with respect thereto, a member mounted on the pedestal movable in a rectilinear path in one plane, a member connected to the first member and movable in a rectilinear path at an angle to the path 25 of movement of the first member and means for connecting the second member to the supporting member.

8. A leveling device including a pedestal, a supporting member mounted on the 30 pedestal and adapted to have universal movement with respect thereto, a member mounted on the pedestal movable in one

plane, a member connected to the first member and movable in a path at an angle to the path of movement of the first member 35 and a member interposed between the second member and the supporting member for connecting the second member to the supporting member.

9. A leveling device including a pedestal, 40 a supporting member mounted on the pedestal and adapted to have universal movement with respect thereto, a member mounted on the pedestal movable in a rectilinear path in one plane, a member mounted on 45 the pedestal movable in a rectilinear path at right angles to the path of movement of the first member, and means for communicating the motion of both members to the supporting member. 50

10. A leveling device including a pedestal, a supporting member mounted on the pedestal and adapted to have universal movement with respect thereto, a member mounted on the pedestal movable in one plane, a member 55 mounted on the pedestal movable in a path at right angles to the path of movement of the first member, and means interposed between the second member and supporting member for communicating the motion of both members to the supporting member. 60

THOMAS A. CONLON.
